COMBINED ACTUATOR AND BRACKET FOR WINDOW CLOSURE

Eldon L. Burn, 2717 S. 107th Ave.,
Omaha, Nebr. 68124

Filed Apr. 12, 1973, Ser. No. 350,398

Term of patent 14 years

Int. Cl. D8—09

U.S. Cl. D8—153

FIG. 1 is a perspective view of my new design for combined actuator and bracket for window closure, said view being taken from the top-rightward-rearward directions;

FIG. 2 is a rearward elevational view;

FIG. 3 is a forward elevational view thereof;

FIG. 4 is a top plan view of my new design, the bottom plan view being a substantial mirror image thereof;

FIG. 5 is a rightward side elevational view of my novel design; and

FIG. 6 is a leftward side elevational view of the design for combined actuator and bracket for window closure.

I claim:

The ornamental design for combined actuator and bracket for window closure, as shown and described.
